UNITED STATES PATENT OFFICE.

THEODORE HUNGER, OF BROOKLYN, NEW YORK, ASSIGNOR TO HIMSELF
AND WILLIAM H. COFFIN, OF SAME PLACE.

THILL-COUPING.

SPECIFICATION forming part of Letters Patent No. 359,973, dated March 22, 1887.

Application filed November 17, 1886. Serial No. 219,151. (No model.)

To all whom it may concern:

Be it known that I, THEODORE HUNGER, of Brooklyn, in the county of Kings and State of New York, have invented a new and Improved 5 Thill-Coupling, of which the following is a full, clear, and exact description.

My invention relates to an improvement in thill-couplings, and has for its object to provide a coupling wherein the thills may be only 10 removed when inclining downward, and wherein in the use of a wrench or other instrument is dispensed with in such removal, which may be accomplished instantly by the simple pressure of a lever attachment.

15 The invention consists in the construction and combination of the several parts, as will be hereinafter fully set forth, and pointed out in the claims.

Reference is to be had to the accompanying 20 drawings, forming a part of this specification, in which similar letters of reference indicate corresponding parts in all the figures.

Figure 1 is a side elevation, partly sectional, of my thill-coupling, and Fig. 2 is a plan view 25 thereof. Fig. 3 is a plan view, partly sectional, of the bolt used in connection with the coupling.

A represents an ordinary jack-clip in position upon the axle *a*, and *B* a thill-iron having attached thereto a portion of the thill *b*. The said thill-iron *B* is provided with a semi-circular lower end, *C*, having a cam-like upper surface, *c*, with a groove, *d*, cut therein, which, when the thills are in their normal position, will assume a vertical line parallel with the face of the clip, as illustrated in Figs. 1 and 35 2, the lower face of the said semicircular end *C* being provided with a central concavity, *D*.

Above the semicircular end *C* the thill-iron 40 *B* is furnished with ears *D'*, integral with the under surface thereof, in which ears a lever, *E*, is journaled, having attached to its upper end a spring, *e*, whose free end is made to bear against the said iron *B*, while the action of said 45 lever *E* is controlled by a set-screw, *M*, adapted to pass through the lever and to a bearing upon the under face of the iron *B*.

The lower end, *F*, of the lever *E* is semicircular in form, its inner flat surface at this 50 point being provided with a concavity, *f*,

adapted to register with the concavity *D* in the semicircular end *C* of the iron *B*, so that when the flat faces of the said iron and lever meet the concavities therein will form a circular aperture adapted to receive the bolt *e'* of 55 the jack-clip *A*.

The outer contour of the united circular portions of the thill-irons *B* and the lever *E* do not constitute a true circle, owing to the eccentric or cam-surface *c* of that end of the 60 iron, and the eye formed by the two cavities *D* and *f* is therefore nearer the bottom surface of the said united portions than the top, the greater thickness of metal being consequently above and to the rear of the eye, the 65 purpose of this arrangement being to render it impossible to detach the thills; even though the spring and set-screw were omitted, when the said thills are in their normal position, but when the thills are lowered below a central line to 70 render their detachment easy, by simply pressing the end of the lever *E* upon each thill-iron and drawing the thills simultaneously forward. The groove *d* forms a means for keeping the bearing-surface of the thill-iron free from dust 75 and grit, thereby to a great extent preventing the wear thereof, as a channel is thus formed to afford egress to foreign matter.

In the use of my coupling I employ the usual-sized bolt, *e'*, which will enter the wings 80 of most jack-clips. To provide against any rattling or noise, however, I form a recess, *h*, in said bolt about centrally the head and the thread, and spring over the threaded portion a rubber ring, *h'*, to a bearing upon the reduced portion of the bolt of such thickness as to make the said bolt of uniform diameter.

It will be observed from the above description, taken in connection with the drawings, that the coupling locks automatically through 90 the attached spring, as the set-screw may be dispensed with, and that the thills may be changed or removed at pleasure, without touching the wheel or using a wrench, and that by any person of ordinary intelligence in a few seconds; 95 again, that the cam-face of the thill-iron will press against the jack-clip when the thills are brought into their normal position, and the heft of the metal being upon the top and at the back of the eye, the coupling is made to bear 100

firmly against the rubber covering of the bolt, thereby obviating any rattling noise and preventing the coupling from becoming loose in backing.

5 In the event the horse should fall the thills are readily detached at once without unhitching the horse.

Having thus described my invention, what I claim as new, and desire to secure by Letters to Patent, is—

1. In a thill-coupling, a thill-iron having its eye formed partially in the iron and partially in a spring-actuated lever pivoted thereto, the said thill-iron having its upper end surface eccentric to said iron and provided with a vertical groove, substantially as shown and described, and for the purpose herein set forth.

2. The combination, with the jack-clip A and rubber-incased bolt e', of the thill-iron B, having its upper end surface provided with a vertical groove, d, and made eccentric with a central concavity, D, in its under surface, the lever E, provided with a concavity, f, in its upper end surface in line with the said concavity D, and the spring e, substantially as

shown and described, and for the purpose herein set forth.

3. The combination, with the jack-clip A and the bolt e', having a rubber collar, h', thereon, of the thill-iron B, having its upper end surface provided with a vertical groove, d, and made eccentric with a central concavity, D, in its under surface, the lever E, provided with a concavity in its upper end surface in the same plane with the said concavity D, the 35 spring e, and set-screw M, substantially as shown and described, and for the purpose herein set forth.

4. The combination, with the thill-iron B, provided with a concavity, D, in its under surface and having its upper end surface eccentric to the concavity D, of the spring-actuated lever E, provided with a concavity in its upper surface registering with the concavity D, substantially as shown and described.

THEODORE HUNGER.
